UNITED STATES PATENT OFFICE.

FRANK BILLINGS AND ROBERT P. GREENLEAF, OF CLEVELAND, OHIO; SAID GREENLEAF
ASSIGNOR TO SAID BILLINGS.

LOADING-MACHINE.

1,322,477.

Specification of Letters Patent. Patented Nov. 18, 1919.

Application filed November 12, 1917. Serial No. 201,630.

To all whom it may concern:

Be it known that we, FRANK BILLINGS and ROBERT P. GREENLEAF, citizens of the United States, and residents, respectively, 5 of Cleveland, in the county of Cuyahoga and State of Ohio, and Cleveland, in the county of Cuyahoga and State of Ohio, have invented a certain new and useful Improvement in Loading-Machines, of which the following is a full, clear, and exact description.

This invention relates to loading machines, and has for its chief object to provide an efficient loading machine adapted particularly for use in mines where the head 15 room of the space in which the machine is working is limited.

More particularly the invention aims to provide a loading machine of the type which includes a material conveying element such 20 as a bucket or shovel, which is designed to be filled with material at the front of the machine and then carried rearwardly over the machine and dumped, the parts being so constructed and operated that as the conveying element is being carried or moved 25 over the machine, either rearwardly while carrying its load, or forwardly after the load has been discharged, it will at no time project beyond a given distance from the 30 mine floor or track, which distance is practically a minimum for a machine of this type, thus enabling the machine to be used in tunnels or drifts of mines wherein the coal or ore is in thin veins.

Still further the invention aims to accomplish the above objects with operating mechanism which is simple in its construction and operation.

Our invention may be briefly summarized 40 as consisting in certain novel details of construction and combinations and arrangements of parts which will be described in the specification and set forth in the appended claims.

In the accompanying sheets of drawings 45 wherein we have illustrated the preferred embodiment of our invention, Figure 1 is a side elevation of the machine showing by dotted lines, different positions of the shovel 50 in its course of travel over the machine; Fig. 2 is a similar view on a reduced scale showing by dotted lines the extreme forward position of the shovel at the end of the filling stroke and in addition the position 55 of the shovel and the tilting bottom

thereof at the extreme end of its rearward stroke, or while the material is being discharged therefrom; Fig. 3 is a rear end view of the machine on the same scale as Fig. 2; Fig. 4 is a side view of the so-called 60 trolley forming a part of the shifting mechanism for the material conveying element; Fig. 5 is a top plan view of the machine, parts being broken away; Fig. 6 is a transverse sectional view substantially along the 65 line 6—6 of Fig. 1, looking rearwardly, the shovel being here shown in elevated position; Fig. 7 is a view similar to Fig. 2, but showing the parts in the positions which they occupy when the shovel is at the end 70 of its forward filling stroke; and Fig. 8 is a front view of the machine.

The machine includes a frame 10 which may be of structural material and provided with wheels 11 which may be ground 75 wheels, or track wheels, in which event they will be flanged, as here shown, and run along the rails of a track indicated conventionally at 12. Supported on this frame 10 is a horizontally movable platform or so-called turntable 13, which is supported on the frame 10 through the medium of rollers 14 which enable the turntable and all the parts supported by it to be turned horizontally about an axis which will be near the 80 rear end of the machine so as to properly position the front working end of the machine with reference to the material to be loaded.

The material conveying element is here 90 shown in the form of a shovel or bucket 15 which is designed to be thrust forwardly so as to scoop up a load of material and then to be retracted before being conveyed rearwardly over the machine to the dumping 95 point. For the purpose of thrusting the shovel forwardly and then retracting it, we employ a reciprocating device in the form of a ram, which as here shown, consists of two parallel side members 16 connected together by transverse rods 17, or other suitable means so as to travel forwardly and rearwardly as one piece. These side members 16 of the ram consist of vertical plates 16^a (see Fig. 6) having at their top and 100 forward edges, peculiarly curved angles 16^b, constituting cams, and having along their lower edges on the exterior thereof, angle members 16^c with racks 16^d, the rack teeth 105 extending from the rear end of the ram for- 110

wardly for about two-thirds the length of the latter. The forward end of rack 16^a is indicated in Figs. 1 and 7 by the short dotted line A. This ram is supported for reciprocating movement in part by stationary track rails 18 which are mounted in fixed position just inside the side members of the ram, and are engaged by rollers 18^a carried by the rear end of the ram in position to engage the upper and lower faces of the rails 18. The ram is supported at the front of the machine by rollers 19 which are stationary as far as rectilinear movement is concerned, and engage rails 20 secured to the inner lower sides of the side members of the ram (see Fig. 6).

For the purpose of shifting the shovel forwardly and rearwardly over the machine, a trolley or carriage is provided, this being supported on the ram so that it may move forwardly and rearwardly relative thereof. This trolley consists of two side castings 21 which are just outside of the side members of the ram, and a cross or connecting casting 21^a which extends from one side casting 21 to the other through slots 16^b in the side members of the ram, the length of the slots shown particularly in Fig. 1 indicating substantially the length of the movement of the trolley on the ram. This trolley is supported and guided by rollers 21^b (see particularly Fig. 6) journaled on the inner ends of short studs 21^c extending transversely through the side castings 21 of the trolley, these rollers engaging and rolling on the upper surfaces of the angle members 16^c which, as before stated, are secured to the lower outer side portions of the side members 16 of the ram.

40 The lower edges of the side castings 21 of the trolley are provided with rack teeth 21^d as illustrated in Fig. 4.

The shovel 15 is connected to this trolley by two telescoping arms 22, each consisting of a forward portion 22^a carrying a block 22^b, and a rearward portion 22^c having a slot which receives the block with a sliding action which will allow the arms to be extended or contracted. The forward ends of the parts 22^a of the shovel shifting arms are pivotally connected at 22^d to the sides of the shovel or bucket 15, and the rear ends of the companion parts 22^c of the arms are pivotally connected to the trolley, the arm members 22^c being in this case journaled on the rear roller supporting studs 21^c carried by the side castings 21 of the trolley (see Fig. 6). At their rear ends the members 22^c of the shovel shifting arms are provided with gear segments 23 which are designed to engage racks 24 carried by and secured along the sides of the turntable 13. As will be subsequently explained, when the trolley is shifted rearwardly relative to the ram, 65 the gear segments 23 engage these racks 24

so as to give the shovel and shovel supporting arms a movement of rotation at the same time that they are given a movement of translation by the movement of the trolley. When the shovel is being swung back over the machine to its lower forward position, the arms swing downwardly until they engage adjustable stops 25 carried by brackets 26 secured to the forward part of the side members of the ram as best shown in Fig. 75 1, these stops holding the shovel and shovel supporting arms in fixed position with respect to the ram during the forward filling and retracting movements, and determining the angularity of the arms and the depth 80 of digging movements as will be apparent.

The shovel 15 as here shown is provided with a bottom which in this case is the digging part of the shovel, with sides, and with a rear wall 15^a which is pivoted at 15^b to what is normally the upper rear corners of the shovel so as to swing inwardly in the manner hereinafter explained. This rear wall 15^a has secured to it a member 15^c having a rearwardly extending hook-like portion 15^d which is designed to hook over a cross shaft 27 extending between the sliding blocks 22^b of the forward members 22^a of the shovel shifting arms 22, (see particularly Fig. 5). This shaft 27 is provided with rollers 28 which are adapted to roll over the upper cam surfaces of the angles 16^b, which as before stated, extend along the upper and forward edges of the side members of the ram.

By reason of the pivotal connection between the shovel and the forward arm members 22^a, and the engagement of the hook 15^d over the cross shaft 27, the shovel is held rigidly between the arm members 22^a until the hook is disengaged from the cross shaft just before the shovel reaches the rear end of its stroke at the upper rear end of the machine.

To shift the ram, trolley and shovel relative to the turntable, and to shift the trolley and shovel relative to the ram, different motive devices and power transmitting mechanisms may be employed, and while we do not wish to be confined to the construction and arrangement here shown, we prefer to employ for these purposes, that is, to fill and empty the shovel and thereby move the shovel through its complete cycle of operation, a single motor 30, which as here shown is mounted at the rear end of the turntable between the side members of the ram. We prefer to use for this purpose an electric motor, although a motor of any other suitable type may be employed. The motor is provided with a forwardly projecting shaft 31, which through a worm 32 and a worm wheel 33 (see Fig. 6) drives a transverse shaft 34 supported in suitable bearings 35 on the turntable near the forward 110 120 125 130

portion thereof. This shaft 34 has secured to its outer ends just beyond and alongside of the turntable, pinions 36, each with a face wide enough to engage the two racks 16^a and 21^a, the former being carried by the ram and the other by a trolley as before explained.

The parts so far described, operate as follows: At the beginning of the filling stroke 10 of the shovel the parts are in the position shown in Fig. 1 with the cross member of the trolley at the forward ends of the slots 16^a in the side members of the ram, and with the pinions 36 about to leave the racks 21^a 15 of the trolley and to engage the racks 16^a of the ram. If the motor is now started, through the shaft 31, worm gearing 32 and 33, and shaft 34, it will rotate the pinions 36, which through their engagement with the racks just mentioned, move the ram, trolley, shovel and shovel supporting arms forward, thus filling the shovel with material. This forward movement can be stopped at any point within the forward limit of movement 25 which is indicated in Fig. 7, and when the shovel is filled, the motor is reversed, moving all the parts rearwardly again to the position shown in Fig. 1.

As soon as the parts reach this position, 30 the rearward movement of the ram is stopped because the rotating pinions ride off or leave the racks 16^a of the ram and at the same time engage the racks 21^a of the trolley. At this point the gear segments 23 at 35 the pivotal axis of the shovel arms are in position to engage the stationary racks 24, and the rollers 28 on the cross shaft 27 engage the cam surfaces of the angles 16^b of the ram, as shown in Fig. 1. There- 40 fore the continued rotation of the pinions shifts the trolley rearwardly relative to the ram as soon as the movement of the ram ceases, and at the same time through the en- 45 gagement of the gear segments 23 with the racks 24, the shovel and shovel supporting arms are swung rearwardly, giving the loaded or filled shovel its rearward movement of translation and movement of rotation previously described, and causing the shovel to 50 travel from the forward end of the machine up over the machine to the rear end thereof. In passing through this path of movement the rollers 28 travel over the curved cam surface of the angles 16^b, allow- 55 ing the shovel supporting arms to telescope so that at no position of the shovel will any part of the latter project a considerable distance above the machine, these cam surfaces being so designed that as the shovel is travel- 60 ing rearwardly and is being gradually turned, the highest point of the shovel travels through a straight line or plane parallel to the mine floor or track on which the machine is run, this plane being indicated by 65 the dotted line B of Fig. 2. The distance

between this plane indicated by the line B and the rails of the track or surface over which the machine is designed to run is no greater than the extreme height of the machine over which the shovel travels and the 70 maximum front and rear dimension of the shovel.

As the shovel nears the rear end of its rearward swinging stroke, the hook 15^e on the pivoted rear wall or door of the shovel 75 leaves the cross shaft 27, and the shovel tilts down on flat horizontal surfaces 37 at the upper rear end of the machine, with what was formerly the rear wall of the shovel now the bottom wall, engaging these surfaces. 80 Just before the rear end of the stroke is reached, abutments in the form of rollers 38 carried by the sides of the shovel engage some diagonally disposed upstanding arms 39 mounted on the ends of a rockshaft 40 at 85 the upper rear end of the machine, this rockshaft having one or more forwardly projecting arms 41 which are beneath the shovel when sliding rearwardly over the arms 37. The engagement of these rollers 90 38 with the arms 39 rocks the shaft 40 and elevates the arm or arms 41, and thus shifts or elevates the pivoted bottom wall (nor- 95 mally the rear wall) 15^a of the shovel to substantially the dotted line position shown at 100 the upper right hand corner of Fig. 2, with the result that the material will be discharged from the shovel when it reaches the end of its stroke. The material will be discharged into a suitable mine car or other 105 receptacle which will be provided for that purpose at the rear of the machine.

Then the motor will be reversed and the trolley or carriage will be moved forwardly, 110 this forward movement of the trolley caus- 105 ing the shovel to move forwardly and down- 110 wardly to the position shown in Fig. 2, the hook 15^e automatically hooking over the cross shaft 27 as before, and as soon as the shovel and shovel supporting arms reach the 115 position shown in Fig. 1, the rotating pinions 36 leave the trolley racks 21^a and engage the rack rams 16^a and therefore move the parts forwardly to again fill the shovel. The action previously described will then be 120 repeated.

Having described our invention, what we claim is:

1. In a loading machine, a frame, a ma- 120 terial conveying element, mechanism for moving said element forwardly so as to re- ceive a load and then rearwardly over the machine so as to dump the material at the rear thereof, said mechanism comprising a ram adapted to be reciprocated, a trolley 125 movable lengthwise of the ram, swinging means connecting the material conveying element to the trolley and rotary means for reciprocating the ram and shifting the trolley relative to the ram. 130

2. In a loading machine, a frame, a material conveying element, mechanism for shifting said element forwardly to fill the same and then moving the same rearwardly over the machine to a dumping point, said mechanism comprising a ram mounted on the frame for reciprocating movement forwardly and rearwardly, a carriage mounted on the ram for movement relative thereto, 10 arms connecting the carriage to the material conveying element, and mechanism for successively shifting the ram on the frame and for shifting the carriage on the ram.
- 15 3. In a loading machine, a frame, a material conveying element, mechanism for moving the same forwardly so as to receive the load and then rearwardly and over the machine to dumping position, said mechanism comprising a ram mounted for forward and rearward reciprocating movement on the frame, a carriage mounted on the ram for forward and rearward reciprocating movement thereof, and telescopic arms 20 connected to the material conveying element and pivotally connected to the carriage.
- 25 4. In a loading machine, a frame, a material conveying element, mechanism for moving the same forwardly so as to receive the load and then rearwardly and over the machine to dumping position, said mechanism comprising a ram mounted for forward and rearward reciprocating movement on the frame, a carriage mounted on 30 the ram for forward and rearward reciprocating movement relative thereto, arms connected to the material conveying element and pivotally connected to the carriage, and rotary means for reciprocating the ram, for 35 shifting the carriage on the ram, and for turning the arms and material conveying element.
- 40 5. In a loading machine, a frame, a material conveying element, mechanism for moving the same forwardly so as to receive a load and then rearwardly and over the machine to dumping position, said mechanism comprising a ram mounted for forward and rearward reciprocating movement on 45 the frame, a carriage mounted on the ram for forward and rearward reciprocating movement relative thereto, arms connected to the material conveying element and pivotally connected to the carriage, and means 50 for reciprocating the ram and then reciprocating the carriage and simultaneously imparting a turning movement to the arms and material conveying element.
- 55 6. In a loading machine, a frame, a material conveying element, mechanism for moving the same forwardly so as to receive a load and then rearwardly and over the machine to dumping position, said mechanism comprising a ram mounted for forward and rearward reciprocating movement on 60 the frame, a carriage mounted on the ram for forward and rearward reciprocating movement relative thereto, arms connected to the material conveying element and pivotally connected to the carriage, said arms being composed of telescoping members.
- 65 7. In a loading machine, a frame, a material conveying element, mechanism for moving the same forwardly so as to receive a load and then rearwardly and over the machine to dumping position, said mechanism comprising a ram mounted for forward and rearward reciprocating movement on the frame, a carriage mounted on the ram for forward and rearward reciprocating movement relative thereto, arms connected to the material conveying element and pivotally connected to the carriage, said arms being composed of telescoping members, and a cam surface for controlling the telescoping 80 of the arms when the material moving element is being moved over the machine.
8. In a loading machine, a frame, a material moving element in the form of a shovel, mechanism for thrusting the shovel forwardly, for retracting the same and moving the same over the machine to dumping position, said mechanism comprising a ram mounted on the frame for forward and rearward reciprocating movement, a carriage 90 movable on the ram, arms pivotally connecting the shovel to the carriage, a motor, and mechanism by which said motor reciprocates the ram and the carriage successively.
9. In a loading machine, a frame, a material moving element in the form of a shovel, mechanism for thrusting the shovel forwardly, for retracting the same and moving the same over the machine to dumping position, said mechanism comprising a ram 95 mounted on the frame for forward and rearward reciprocating movement, a carriage movable on the ram, arms pivotally connecting the shovel and the carriage, a motor, and mechanism by which said motor reciprocates the ram and simultaneously reciprocates the carriage and turns the arms.
10. In a loading machine, a frame, a material moving element in the form of a shovel, mechanism for thrusting the shovel forwardly, for retracting the same and moving the same over the machine to dumping position, said mechanism comprising a ram mounted on the frame for forward and rearward reciprocating movement, a carriage 110 movable on the ram, arms pivotally connecting the shovel and the carriage, motive means, and mechanism by which said motive means reciprocates the ram and carriage and turns the arms, comprising rack and gear driving means between the motive means, ram, carriage and arms.
11. In a loading machine, a frame, a material moving element in the form of a shovel, mechanism for thrusting the shovel 115
- 120
- 125
- 130

- forwardly, for retracting the same and moving the same over the machine to dumping position, said mechanism comprising a ram mounted on the frame for forward and rearward reciprocating movement, a carriage movable on the ram, arms pivotally connecting the shovel to the carriage, a motor, and mechanism by which said motor reciprocates the ram and carriage and turns the arms, 5 said mechanism comprising a motor driven gear, racks carried by the ram and carriage respectively and adapted to be engaged by said gear, a rack carried by the frame, and a gear rotatable with the arms and adapted 10 to engage said last named rack.
12. In a loading machine, a frame, a shovel adapted to be filled with material at the front of the machine and to be swung over the machine to dumping position, a 15 ram movable forwardly and rearwardly of the frame, the ram having a runway, a trolley movable along the runway of the ram, swinging arms connecting the shovel to the trolley, and a single motor for shifting the ram back and forth and for shifting the trolley along the runway of the ram.
13. In a loading machine, a frame, a shovel adapted to be filled with material at the front of the machine and to be swung 20 upwardly and rearwardly over the latter to dumping position, a ram movable forwardly and rearwardly of the frame, a trolley mov-
- able relative to the ram, swinging means connecting the shovel to the trolley and adapted to be rotated to swing the shovel 35 over the machine, said swinging means being composed of relatively movable parts, and means whereby said parts are moved relatively during the swinging movements of the shovel to increase and decrease the 40 effective length of said parts.
14. In a loading machine, a frame, a shovel adapted to be filled with material at the front of the machine and to be swung upwardly and rearwardly over the latter to 45 dumping position, a ram movable forwardly and rearwardly of the frame and provided with a trolley runway and with a cam surface, a trolley adapted to be shifted along the runway of the ram, swinging means connecting the shovel to the trolley and adapted to be rotated to swing the shovel over the machine, said swinging means being composed of relatively movable parts by which the effective length of the swinging means 50 may be increased and decreased as the shovel is swung over the machine, said swinging means having a part adapted to travel over the cam surface of the ram to cause such relative movement of said swinging means. 55

In testimony whereof we hereunto affix our signatures.

FRANK BILLINGS.
ROBERT P. GREENLEAF.
